OXYGEN TENT OR LIKE ENCLOSURE

George William Higgs, London, England

Application December 28, 1948, Serial No. 67,699
In Great Britain October 27, 1947

8 Claims. (Cl. 128—1)

1

This invention relates to oxygen tents and like enclosures for maintaining infants and small children in a controlled atmosphere as, for example, when travelling in aircraft at altitudes where a supply of oxygen must be given to maintain comfort, or in hospitals and the like for medical purposes. The object of the invention is to provide a tent or enclosure which is collapsible and, when collapsed, is extremely compact so that it may be readily transported.

According to the invention, an oxygen tent or like enclosure for the purpose herein set forth comprises a base and side and end walls of gas-proof sheet material, stiffening means for said base and walls, and flaps extending along the upper edges of said side and end walls, the said flaps being adapted for connection one to another by fastening means at the corners of the enclosure to form a continuous in-turned rim about the top of said enclosure.

The base and walls are preferably stiffened by metal frames, and the enclosure conveniently comprises two separable units, one consisting of stiffened side walls connected by flexible gas-proof material at their end and bottom edges to form ends and a base, and the other consisting of a stiffened base and stiffened end walls, each said unit being adapted to fold flat when separated from the other unit, and said other unit fitting within the first unit when both are extended.

The invention is hereinafter described with reference to the accompanying drawings, in which:

Figure 1 is a perspective view of an oxygen tent according to the invention for use in aircraft;

Figure 2 is a perspective view of the base and end stiffeners of the tent shown in Figure 1;

Figure 3 is a perspective view of the tent in a fully folded condition;

Figure 4 is a perspective view similar to Figure 1 but with parts broken away to show the construction; and

Figure 5 is a detail.

Referring to the drawings, the oxygen tent comprises, when extended an open-topped enclosure the opening of which can be covered, if desired, by a separate transparent cover, and is adapted to fold substantially flat when out of use, thus facilitating transport and storage.

The tent is of rectangular parallelepiped shape, and consists of two main units, one comprising the sides 10, which are stiffened, and a connecting strip of flexible sheet material ex-

2

tending between the end and bottom edges of the sides to form an outer base 11 and outer end walls 12, and the other, which serves to hold the sides spaced apart, comprising a stiffened inner base 13 and two stiffened inner end walls 14.

The sides 10, inner base 13 and inner end walls 14 each comprise a frame of round metal bar, conveniently $\frac{1}{8}$ th inch bright mild steel the frame being enclosed in an envelope of gas-proof and fireproof flexible sheet material, such as a glass weave coated with a plastic substance. One of the side frames is shown at 15 in Figure 4, parts of the frame 16 of the inner base 13, and of the frame 17 of one inner end wall 14, being shown in the same figure. Padding material 18, such as kapok, is provided in the envelopes of the sides 10, inner base 13 and inner end walls.

A transparent window 19 is provided in one side 10. Along the upper edges of the sides 10 and outer end walls 12 of the tent, flaps 21 are provided which, when held together at the corners by quick-release fasteners 22, form a continuous in-turned rim about the edge of the tent.

A cover 23 is provided, which is adapted to be secured to the rim formed by the flaps 21, by additional quick-release fasteners 24 at the corners, and further, similar fasteners 25 near the longitudinal centre of the tent. The cover 23 is of transparent material strengthened around its edge, and across the middle by strips 26 of material similar to that constituting the covering of the tent.

A shackle 27, mounted on a plate 28 is secured to the centre of the lower edge of one side of the tent, the plate being located outside the covering, and bolted, through the covering, to an internal plate 31 carrying a shackle 32, the arrangement being such that the lower frame member of the side is clamped between the plates 28 and 31 (see Figure 5). The outer shackle serves for anchoring the tent in position in an aircraft, and the inner shackle for the securing of a fireproof blanket 30 adapted to be wrapped around an infant in the tent. Additional shackles such as that shown at 33 in Figure 4 may be mounted on the tent to provide supplementary anchorage points, and carrying handles 34 are mounted at the upper edges of the sides.

An oxygen supply fitting 35 is mounted on one side wall 10, the fitting comprising a nozzle 36 projecting into the tent, a sight feed device 37, and a connection for a flexible supply pipe 38.

In use, the two units are assembled together, and held in position by quick-release fasteners 39 which secure the inner end walls 14 to the outer ends walls 12. The tent is intended to be placed in an aircraft so that it lies transversely of the aircraft with the main anchorage, shackle 27 aft, the infant who occupies it being wrapped in the fireproof blanket, the ends of which are connected together by suitable clips or catches, indicated at 41. In the event of the aircraft crashing, the tent is held by the anchorage shackle against overturning, and the blanket 30 prevents the infant from being thrown violently against the forward side of the tent.

The cover 23 need not be fastened down permanently or completely, since oxygen tends to remain in the tent due to its density being greater than that of air, but it serves to reduce the disturbance of the atmosphere in the tent, with consequent loss of oxygen, due to irregular flight of the aircraft, or other causes.

When the tent is not in use, the flaps 21 are separated at the corners by releasing the fasteners 22, and the inner base 13 and inner end walls 14 are removed after releasing the fasteners 39. The unit comprising the inner base 13 and inner end walls 14 is folded as shown in Figure 2, and the other unit is folded as shown in Figure 3, one side 10 being folded down on the outer base 11, and the second side 10 being folded down over the first.

The device according to the invention is readily portable, is compact when out of use and, when in use, provides an enclosure in which an infant can be maintained in a controlled atmosphere but in which the infant is readily accessible for feeding and other attention, and in which there are no hard internal surfaces or projections which might injure the infant if it struck against them owing, for example, to violent movements of an aircraft in which it was travelling.

What I claim is:

1. An oxygen tent comprising a base and side and end walls of flexible gas-proof sheet material, frame means for supporting said base and walls, a flap extending along the upper edge of each of said walls, fastening means at the ends of said flaps for securing together the ends of each two flaps which meet at a corner of the tent so that said flaps form together a continuous inwardly-directed flange partially enclosing the top of the tent, and an oxygen inlet device mounted on one of said walls.

2. An oxygen tent comprising a base and side and end walls of flexible gas-proof sheet material, a stiffening unit inserted within said tent and comprising a base frame and end frames hingedly connected to said base frame, flaps extending along the upper edges of each of said walls, fastening means at the ends of said flaps for securing together the ends of each two flaps which meet at

a corner of the tent so that said flaps form together a continuous inwardly-directed flange partially enclosing the top of the tent, and an oxygen inlet device mounted on one of said walls.

3. An oxygen tent comprising a base and side and end walls of flexible gas-proof sheet material, the side walls comprising envelopes enclosing stiffening frames, a stiffening unit inserted within said tent and comprising a base frame and end frames and an envelope of gas-proof sheet material enclosing said base and end frames and connecting them for folding movement with respect to each other, flaps extending along the upper edges of each of the side and end walls, fastening means at the ends of said flaps for securing together the ends of each two flaps which meet at a corner of the tent so that said flaps form together a continuous inwardly-directed flange partially enclosing the top of the tent, and an oxygen inlet device mounted on one of the side walls.

4. An oxygen tent according to claim 3, wherein padding is provided in the envelopes of gas-proof material enclosing the stiffening frames.

5. An oxygen tent according to claim 3, wherein a transparent window is provided in one side wall of the tent.

6. An oxygen tent comprising a base and side and end walls of flexible gas-proof sheet material, frame means for supporting said base and walls, a flap extending along the upper edge of each of said walls, fastening means at the ends of said flaps for securing together the ends of each two flaps which meet at a corner of the tent so that said flaps form together a continuous inwardly-directed flange partially enclosing the top of the tent, an oxygen inlet device mounted on one side wall of the tent, a flexible cover, and readily releasable fastening means securing said flexible cover to the flaps forming the inturned flange.

7. An oxygen tent according to claim 3, wherein a shackle is provided externally at the lower edge of one side, and is anchored to the stiffening frame of that side.

8. An oxygen tent according to claim 7, wherein a second shackle is provided internally of the tent at the lower edge of one side, and the fixing means for both shackles comprise plates to which the shackles are hinged, the said plates together forming a clamp secured by bolts to the stiffening frame.
